UNITED STATES PATENT OFFICE.

CHARLES PRACHE, OF PARIS, FRANCE.

PROCESS OF PREVENTING INCRUSTATION OF PIPES.

Application filed October 24, 1919. Serial No. 332,903.

To all whom it may concern:

Be it known that I, CHARLES PRACHE, of 55
106 Boulevard Haussmann, Paris, France,
engineer, have invented new and useful Im-
provements in Processes of Preventing In-
crustation of Pipes, which improvements are
fully set forth in the following specification.

It is known that the evaporating appa- 10
ratus employed in industry for the evapo-
ration of liquids or for the distillation of
water become inefficient owing to the deposit
of calcium and other salts upon the heating
surfaces. Such deposits besides affecting
the efficiency of the apparatus cause frequent
15 stoppages for cleaning purposes which is
always a difficult and imperfect operation.

This invention has for its object a method 20
for use in connection with evaporating appa-
ratus by which these difficulties are avoid-
ed and incrustation prevented by automatic-
ally and continuously cleaning the heating
surface.

According to this invention cleaning is 25
effected by the aid of a powder such as sand
or glass or other equivalent substance having
no chemical action upon the liquid to be
evaporated, the substance is added to the
solution which is circulated at a speed such 30
that the substance is drawn by the solution
into contact with the heating surface.

The apparatus capable of use in carrying 35
out the invention is illustrated in the ac-
companying drawing which is a vertical
section.

35 The apparatus comprises a number of
parallel tubes 1 so arranged that they can
be heated on the outside and within which
the liquid to be concentrated circulates. The
tubes are carried by two plates 2 and are ar- 40
ranged within a casing 3 which forms the
heating chamber; heating steam is admitted
through the tube 4 and condensed steam
passes out through the tube 5.

45 6 and 7 are chambers fixed to the plates
2. Into the bottom of the lower chamber
leads a tube 8 which is connected to a tube
9 leading from the upper chamber 7 by pipes
10 and 11; a displacer such as a pump or 50
screw 12 or its equivalent and driven by a
belt or electric motor is located near to the
bottom of the apparatus for the purpose of
continuously forcing liquid in the pipe 10
through the pipe 11 towards the chamber 6.

Liquid to be concentrated is led into the

apparatus through a tube 13 while an over- 55
flow 14 allows continuous outflow of the con-
centrated liquid and regulates the level of
liquid in the apparatus.

The apparatus operates as follows:

The apparatus is filled with liquid to be 60
concentrated through the tube 13 until liquid
overflows through the overflow 14.

A certain quantity of fine sand or its 65
equivalent is introduced through a door 16
and falls into the liquid through the tube 10;
the door is then closed and the circu-
lating pump 12 put into action; liquid cir-
culates in the direction indicated by the 70
arrows 17 and owing to the rapidity of the
circulation the sand remains in suspension in
the liquid and circulates through the appa-
ratus while intimately mixed with it. When
circulation is established steam is admitted 75
through the tube 4; the steam condenses
around the tubes and passes out as water
through the tube 5 while a weight of water
substantially equal is evaporated from the
liquid circulating in the evaporating appa- 80
ratus. The resulting steam passes out
through the tube 15.

The sand maintained in suspension in the 85
liquid keeps the tubes perfectly clean by
frictional contact and removes any deposits
of lime which tend to fix themselves on the
tubes.

While the apparatus is at work liquid to 90
be concentrated is continuously introduced
into the apparatus through the tube 13 in
order to compensate for the weight of the
water evaporated and in order to cause the
outflow of concentrated liquid through the 95
overflow 14.

In order to prevent sand passing out 100
through the overflow 14, the inlet provided,
consists of a portion 18 of a size sufficient
to reduce the speed of the rising liquid to a
speed such that the grains of sand are not
drawn upwards.

When after a stop the apparatus is again 105
set in action, steam is first injected through
the tube 19 with the object of placing any
sand which has deposited at the bottom in
suspension in the liquid.

Claim:

The process of preventing incrustation of 110
pipes through which a liquid, containing
solids in solution, to be evaporated circu-
lates which consists in introducing into the

liquid an abrasive in comminuted form, said abrasive being insoluble and chemically neutral with respect to the liquid, in maintaining the abrasive in suspension in the liquid 5 so as to circulate with it through the pipes by rapidly propelling the liquid and abrasive mechanically under the influence of heat,

and in replenishing the liquid to compensate for evaporation of same and to expel concentrated solution from the circulating system while retaining the abrasive therein.

In testimony whereof I have signed this specification.

CHARLES PRACHE.
